(57) **CLAIM**

The ornamental design for a label dispenser unit, as shown and described.

DESCRIPTION

FIG. 1 is a first perspective view of a label dispenser unit; FIG. 2 is a front view of the label dispenser unit shown in FIG. 1;

FIG. 3 is a rear view of the label dispenser unit shown in FIG. 1;

FIG. 4 is a right side view of the label dispenser unit shown in FIG. 1;

FIG. 5 is a left side view of the label dispenser unit shown in FIG. 1;

FIG. 6 is top view of the label dispenser unit shown in FIG. 1; and,

FIG. 7 is a bottom view of the label dispenser unit shown in FIG. 1.

The broken lines shown in the drawings represent portions of the label dispenser unit that form no part of the claimed design.
